UNITED STATES PATENT OFFICE.

MARTIN HALFPENNY, OF PONTIAC, MICHIGAN, ASSIGNOR TO CANNON METAL WHEEL WORKS, LIMITED, OF PONTIAC, MICHIGAN, A CORPORATION OF MICHIGAN.

SHAFT-COUPING.

SPECIFICATION forming part of Letters Patent No. 725,957, dated April 21, 1903.

Application filed August 2, 1902. Serial No. 118,030. (No model.)

To all whom it may concern:

Be it known that I, MARTIN HALFPENNY, a citizen of the United States, residing at Pontiac, county of Oakland, State of Michigan, 5 have invented a certain new and useful Improvement in Shaft-Couplers; and I declare the following to be a full, clear, and exact description of the invention, such as will enable others skilled in the art to which it pertains to 10 make and use the same, reference being had to the accompanying drawings, which form a part of this specification.

My invention relates to an improvement in shaft-couplers for vehicles shown in the accompanying drawings, and more particularly set forth in the following specification and claim.

Referring to the drawings, Figure 1 is a side elevation of the shaft-coupler, showing it engaged with the shaft and locked as it would be when secured to the buggy. Fig. 2 is a similar view showing it unlocked for the purpose of disengaging it from the buggy. Fig. 3 is an inverted plan view of the coupler.

25 Referring to the letters of reference shown on the drawings, A represents the shaft of a buggy or other vehicle; B, the shaft-iron, which extends beyond the end of the shaft, terminating in an arc of a circle at B' for the purpose of engaging a rubber bushing C, sleeved on the bolt D, engaging the buggy.

B² is a swinging arm pivoted at b, and likewise constructed on an arc of a circle, the construction being such that the parts B' and 35 B² are adapted to completely encircle the bushing C when the part B² is closed.

D is a lever pivoted at d to the lug b', formed integral with the swinging arm B². At d' the lever is bent outward to form a convenient thumb-piece by which it may be oper-

ated. The lever D is provided at its forward end with a raised portion d², upon which the free end of the spring E bears.

E is a spring secured to the shaft-iron at a, the opposite end being free to bear against 45 the end of the lever near its pivotal connection with the swinging arm.

The operation of the device will be readily understood from an examination of the drawings. To engage the shafts to a vehicle, the 50 lever D is thrown down, so that the swinging arm may be open sufficiently to receive within its jaws the bushing C. The lever is then thrown up against the shaft-iron, the movement of which causes the jaws to close around 55 the bushing, thereby engaging the shafts to the vehicle. The action of the spring serves to hold the locking-lever in position when closed. The bushing acts as an antirattler, and the connection between the shafts and 60 the vehicle is such that play of the parts is avoided.

Having thus described my invention, what I claim is—

In a shaft-coupler, the shaft-iron B, the 65 fixed jaw B' formed integral therewith, the swinging jaw B² pivoted to the fixed jaw and provided with an arm b', a lever D pivoted at d to the arm b' and provided with a raised portion d², and a leaf-spring E secured to the 70 shaft-iron at one end, the other end being free to bear on the raised portion d² of the lever, substantially as described.

In testimony whereof I sign this specification in the presence of two witnesses.

MARTIN HALFPENNY.
